UNITED STATES PATENT OFFICE.

ABRAHAM G. JENNINGS, OF BROOKLYN, NEW YORK.

DESIGN FOR A NUBIA.

SPECIFICATION forming part of Design No. 13,317, dated September 26, 1882.

Application filed August 23, 1882. Term of patent 14 years.

To all whom it may concern:

Be it known that I, ABRAHAM G. JENNINGS, of Brooklyn, county of Kings, and State of New York, have invented a new and original 5 Design for Nubias, of which the following is a specification.

Figure 1 represents a face view of my new design for a nubia, and Fig. 2 a reverse view of the same.

10 This invention relates to a new design for a nubia or similar fabric; and it consists in the novel configuration of the meshes composing the same.

The body of the nubia is composed of meshes 15 *a a*, made of ordinary worsted interlooped, as shown, with meshes *b b*, made of corded threads. The meshes *b* of the corded threads show on the face of the fabric, Fig. 1, an upper zigzag row and below that downwardly-extending

loops. On the reverse of the fabric these corded meshes appear to be series of upright loops joined by threads that cross each other, and from which further loops extend downward at the point of crossing. The threads of the meshes *a* are united in the same manner as 25 those of the meshes *b*.

I claim—

1. The design for a nubia, the same consisting of meshes *a* of plain worsted and meshes *b* of corded fabric, substantially as shown. 30

2. The design for a nubia, having meshes *b*, which at the face of the nubia form an upper zigzag row with downwardly-projecting loops, substantially as shown.

ABRAHAM G. JENNINGS.
